DESIGN FOR A HAT

M. Rudulph Norton, Birmingham, Ala.

Application February 5, 1940, Serial No. 90,040

Term of patent 3½ years

To all whom it may concern:

Be it known that I, M. Rudulph Norton, a citizen of the United States and residing at Birmingham, in the county of Jefferson and State of Alabama, have invented a new, original, and ornamental Design for a Hat, of which the following is a specification, reference being had to the accompanying drawing, forming part thereof, and in which

Fig. 1 is a top perspective view of a hat, showing my new design,

Fig. 2 is a perspective view from below,
Fig. 3 is a side elevational view,
Fig. 4 is a rear elevational view and
Fig. 5 is a side view in perspective, looking upwardly upon a somewhat smaller scale than Fig. 4.

I claim:

The ornamental design for a hat, substantially as shown.

M. RUDULPH NORTON.
